UNITED STATES PATENT OFFICE.

JOHN B. MITCHELL, OF PORTLAND, MASSACHUSETTS, ASSIGNOR OF ONE-FOURTH TO STEPHEN C. PERRY, OF SAME PLACE.

TOBACCO-CUTTER.

SPECIFICATION forming part of Letters Patent No. 434,194, dated August 12, 1890.

Application filed March 24, 1890. Serial No. 345,127. (No model.)

To all whom it may concern:

Be it known that I, JOHN B. MITCHELL, of Portland, in the county of Suffolk and State of Massachusetts, have invented a new and 5 useful Improvement in Tobacco-Cutters; and I do hereby declare that the following is a full, clear, and exact description of the same.

My invention is an article adapted to the use of smokers, and is designed specially for 10 the cutting of plug-tobacco or tobacco in twist form, for the purpose of reducing it to such a condition as to allow of its being used in a pipe.

Prior to my invention it has been customary to cut off from the plug or twist small 15 pieces of tobacco by the use of an ordinary pocket-knife and then to crumble the pieces so cut in the hands, placing the tobacco thus crumbled into the bowl of the pipe. This 20 method is very objectionable for the reason that the hands are soiled by contact with the tobacco, the blade of the pocket-knife is not in a condition to be used for any other purpose, and a waste of tobacco very often ensues 25 in view of the fact that if more tobacco is cut off than is found necessary to fill the pipe the remainder is wasted.

It is the object of my invention, first, to provide a simple form of cutter which shall be 30 adapted to be carried conveniently in the pocket and to cut off the tobacco so as to render crumbling unnecessary, and, secondly, to provide in connection with the cutter a box adapted to receive the tobacco as it is cut, 35 and from which the pipe may be filled without necessitating a waste of any of the tobacco, that which remains being retained in the box until required.

A further object is to provide not only for 40 the cutting of ordinary pieces of tobacco, but also for the reduction of small pieces, all of which will be hereinafter more particularly shown and described.

In the accompanying drawings, Figure 1 45 represents the simplest form of my invention. Fig. 2 represents the cutter, located within a simple form of pouch. Fig. 3 is a modified form of the cutter. Fig. 4 represents a tobacco-box with my improved cutter embodied 50 therein. Fig. 5 represents another form of

pocket-pouch for the cutter, this pouch containing also a space adapted to be used for matches.

In the accompanying drawings, which illustrate some of the forms of my invention, the cutter proper is shown at A, and consists, as in Fig. 1, of a plate of metal, which may be of any desired shape, though I prefer to make it round, and this plate is provided with a series of radiating slots or openings, the walls 60 of these slots constituting cutting-edges. While I have shown in Fig. 1 these slots as radiating from the center, I desire to it be understood that I may provide openings of any desired shape and number, so long as the 65 walls of the openings constitute cutters, which are adapted to act upon the tobacco and to reduce the same to a condition adapted for the use of smokers. These cutting walls or points may be in the same plane or they may 70 be arranged alternately in different planes, being slightly out of line, so as to increase or diminish the amount of cut in operation. This action of the cutters may also be regulated whether the cutters be in the same or 75 different planes by the force employed by the user in pressing the tobacco against the cutting-points.

Instead of the cutting-plate being formed in one piece, as shown, I may strengthen it by 80 providing it with a rim, as shown at a, Fig. 2, and securing this rim to one of the faces of the plate.

In another form, Fig. 3, I may provide a cast ring having ribs a' formed therewith of approximately V shape in cross-section and tapering inwardly toward the center, and to this rim secure the cutting-plate, which may in this case be of lighter metal; and it will be seen that the cast projections will operate 85 to sustain the cutting-points without in any way interfering with them. In this case the cutting-plate may be made in one piece or in sections, as may be preferred. Instead of the projections extending from the rim, I may 90 strike the cutting-plate up with depressions upon one side, thus forming ribs a², which extend longitudinally of the cutting-point and serve to give them strength.

In order to provide for the cutting of small 100

pieces of tobacco, which could not be used on the regular openings in the plate on account of the size of the central opening, I provide at the base of one or more of the cutting-
5 points a series of cutting-edges, which will accommodate the smallest pieces of tobacco, and thus prevent any cause for waste. These smaller openings 1, the walls of which form the cutting-edges, may likewise be of any de-
10 sired shape or number.

In order to carry the simple form of cutter conveniently, I provide the pocket-pouch shown in Fig. 2 at *c*, which protects the cutting-edges and prevents them from engaging
15 with the fabric of the pocket. The pouch also serves as an advertising medium, as the outside space on the pouch enables the manufacturer or dealer to not only advertise his own goods, but also to add an explanation as
20 to the operation and advantages of the cutter.

Instead of the simple form of pouch shown, I may provide a match-box, as shown in Fig. 5, with a pocket in rear thereof adapted to contain the cutter, and as in the case of the
25 simple form of pouch the outside surfaces of the match-box and the inside surfaces provide ample space for advertising purposes.

In the simple form of cutter which I have heretofore described, the cutter is placed in
30 one hand or the other and the tobacco is taken in the other hand and pressed against the center of the cutting-plate, being given a twisting motion, first in one direction and then in the other, and, as has been stated, the
35 amount of tobacco of each cut may be regulated by the character of the cutting-edges or by the amount of pressure placed upon the tobacco by the hand of the operator in forcing it against the cutting-edges. I have found
40 by experience that tobacco cut in this way puts the tobacco in prime order for smoking without requiring it to be rolled or rubbed in the hand, and that it will light quicker and remain lighted much better than when cut
45 with a knife and crumbled in the usual manner.

In order to prevent a waste of tobacco, I have provided a receptacle which I have shown in Fig. 4, at *d*, with a hinged top *e*,
50 having a depending flange. I do not limit myself as to the form of the receptacle or its size, and instead of the cover being hinged it may slide on or be secured in any suitable

way. In the top of this cover, I arrange my cutting-plate, as shown at *f*. In case the material of the box will be sufficient for the purpose as to strength and durability, I may arrange my cutting-points directly therein, but in case a box is used of cheap material I make my cutting-plate separate and secure it there-
55 to. In order to close the openings in the cover and prevent the tobacco from falling out, I provide a supplemental cover *i*, which fits over the openings in the first cover, both covers being secured by a suitable fastening.
60 The tobacco is reduced to a proper condition for smoking in the manner heretofore described, the supplemental cover being thrown back so that access may be gained to the cutter and then the pipe is filled from the cut
65 tobacco, the excess not used at the time remaining in the box until desired.

It will be understood that the tobacco-box may contain, if desired, a match-box or a lighting device, or anything of the kind which
70 may be of use to the smoker.

Having thus described my invention, what I claim is—

1. In combination with the cutting-plate, a rim and a series of projections formed with
80 the rim and extending inwardly in contact with the surface of the plate for sustaining the cutting-points, substantially as described.

2. In combination, a receptacle, a cutting-plate hinged to said receptacle and constituting
85 a cover therefor, said plate having openings to form cutters, and a cover for the openings hinged to the cutting-plate, substantially as described.

3. In combination with a cutter-plate having a series of openings or slots radiating from the center, the wall of said slots forming cutting-edges, substantially as described.
90

4. In combination with a cutter-plate having a series of cutting-points, supplemental cutters formed by slotting the base of one or more of the points, whereby smaller pieces of tobacco may be reduced to the proper condition, substantially as described.
95

In testimony whereof I have signed my name to this specification in the presence of two subscribing witnesses.

JOHN B. MITCHELL.
